Primary Examiner — Robin V Webster*(74) Attorney, Agent, or Firm* — Larson & Larson, P.A.; Frank Liebenow; Justin P. Miller**CLAIM**

The ornamental design for a paint tray with rounded edges, as shown and described.

DESCRIPTION

FIG. 1 is a perspective view of a paint tray with rounded edges showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a sectional view along lines 8-8 of FIG. 6 thereof;

FIG. 9 is a perspective view of a second embodiment of my paint tray with rounded edges;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof; and,

FIG. 16 is a sectional view along lines 16-16 of FIG. 14 thereof.

FIGS. 9-16 show views of a second embodiment of my claimed design as depicted in FIGS. 1-8, having the same tray size and shape, the difference consisting of a modified leg structure.

The broken line showing in FIGS. 1, 6, 9 and 14 is included for the purpose of illustrating and forms no part of the claimed design.
